UNITED STATES PATENT OFFICE.

PAUL RICHERT, OF BERLIN, GERMANY.

FARE-INDICATOR.

No. 901,558.

Specification of Letters Patent.

Patented Oct. 20, 1908.

Application filed May 22, 1907. Serial No. 375,021.

To all whom it may concern:

Be it known that I, PAUL RICHERT, a subject of the German Emperor, residing at Berlin, in the Kingdom of Prussia, German Empire, have invented new and useful Improvements in Fare-Indicators, of which the following is a specification.

My invention relates to improvements in fare-indicators for hired vehicles.

10 The purpose of a fare-indicator is to indicate the fare which is to be paid by the hirer of the vehicle for the distance traveled, the time occupied by the journey, any additional amounts due for luggage, empty return journeys, and the like, the total sum of the payments, the total number of journeys or hires, etc., these indications being made partly by automatic means, and partly by the driver.

15 In apparatus of the kind employed hitherto the indications have been made either with the aid of pointers moving intermittently over fixed dials bearing suitable numbers, or with the aid of intermittently moved disks or wheels bearing numbers or other indications, on their peripheries, which are caused to appear in succession in an aperture, or with the aid of intermittently rotated number-drums bearing the numbers on their cylindrical surfaces, or with the aid of suitably 20 printed bands which are wound on and off drums or rollers so as to move past apertures. It is very essential that these numbers, especially those which are intended for the information of the passenger, should be 25 made as large as possible, in order to enable them to be read clearly in a bad light, such as in the twilight. But the use of large-sized numbers causes great difficulties of construction with the means hitherto available.

30 Even if the numbers on the disks or drums be limited to the range of 0 to 9, the use of numerals having a height of 25 millimeters would necessitate disks or drums having diameters of at least 95 mm., and 85 mm., respectively. The indication of the fare would 35 require three such disks or drums, so that the fare indicators would have to be at least double the present size. Further, the use of such large disks or drums would entail other 40 difficulties in construction. The intermittent movement of such large disks or drums would necessitate comparatively large accelerating impulses from the low-powered sources of energy, such as clockwork, which 45 are at present available for use. Then again 50 the momentum of such large disks or drums

would have to be suddenly destroyed in the stoppage of these. Similar difficulties would also be caused by the use of large disks or drums in those cases where these are returned 60 to the zero-position by means of a counter-acting-spring, or of a cam or the like on the axle of the disk or drum.

Now the present invention has for its object to provide apparatus which allows of the 65 use of numbers of very large size, with only very small accelerating impulses for progressive movement, and which while having a comparatively very small bulk is capable of being readily returned into the zero-position. 70 The improved apparatus is simple and certain in operation and easy to control and adjust.

According to the present invention, instead of employing the constructional devices as used hitherto in fare-indicators for the purpose of giving the various indications, I employ apparatus specially adapted and designed for the present requirements and particularly for obviating erroneous indications 75 due to the jolting of the vehicle. In the improved apparatus the indications are recorded by means of a check mechanism, and are readily returned to zero.

The accompanying drawings illustrate by 80 way of example a practical form of apparatus constructed according to this invention and designed to indicate the fare to be paid by the hirer of the vehicle, said fare being calculated on the distance traveled, or on the 85 time occupied by the journey, or on both these factors together.

Figure 1 is a section on the line A—A of Fig. 3; Fig. 2 is a section on the line B—B of Fig. 3; Fig. 3 is a front elevation of Fig. 1 95 on a smaller scale; Fig. 4 is a section on the line C—C of Fig. 1 on the same scale as Fig. 3.

The improved indicating-apparatus consists of three counters, the first of which may be arranged to indicate either 0, 10, 100 20 . . . 90 pfennigs, or centimes, or cents, or other fractions of a desired decimal coinage, or 0, 1, 2 . . . 11 pence, or 0. 3. 6. 9 . . . 9 pence of a duodecimal coinage. The second counter may be arranged to indicate amounts 105 of 0, 1, 2 . . . 9 marks, or francs, or dollars, or shillings, or 0, 1, 2 . . . 18, 19 shillings, while the third counter may indicate amounts of 10, 20 . . . 90 marks or francs, dollars or shillings, &c., or amounts of 0, 1, 2, . . . 9 110 pounds sterling.

The apparatus shown is arranged for deci-

mal coinage (viz: pfennigs, centimes or cents) and it is assumed that the fares increase by successive single increments of 10 pfennigs, centimes or cents, and further that the second counter indicates amounts of 0, 1, 2 . . . 9 marks or francs, &c., while the third counter indicates amounts of 0, 10 . . . 90 marks or francs, &c.

- The numbers to be indicated by each counter are marked on the fronts and backs of plates $a-b-c$ which are pivoted by means of pins a^1, b^1, c^1 in the end flanges of rollers a^2, b^2, c^2 , in such a manner that the lower half of each number appears on the front of one plate, and the upper half of the same number appears on the back of the next following plate, so that the two halves together form the said number. Preferably the plates have short extensions r beyond their pivots, which extensions are but slightly shorter than one-half the distance between two adjacent pivot pins a^1, b^1 or c^1 , so that two adjacent plates may form a practically continuous surface when in alinement as shown at the right-hand portion of Fig. 1. The rollers that carry the plates are mounted side by side on a common axle, and are moved forwards, by means of devices hereinafter described, each time through a distance such as will bring each number-plate into the place vacated by the one immediately preceding.

Of the two foremost plates of each counter, one hangs always vertically downwards so that the lower half of the number on its back before turning downward, is visible to the passenger, while the next following plate stands vertically upwards and presents its front and the upper half of the corresponding number to the view of the passenger. The upwardly directed number plate is prevented from falling over by a stop or finger a^3, b^3 , or c^3 , as the case may be. When now the counter is advanced one division, the last-mentioned number-plate is moved down through a distance sufficient to bring its upper edge below the lower edge of the finger a^3, b^3, c^3 , as the case may be, and thus allow the plate to fall over and present the lower half of the next following number to the view of the passenger, while at the same time the next following plate is advanced to an extent sufficient to bring its front (which bears the upper half of the said number) into the same plane as the front of the plate that has just fallen over. The two plates together show the next following number.

The plate which is intended to fall over at the next advance of the mechanism, is retained up to the instant of such advance by the finger a^3 , or b^3 , or c^3 , as the case may be, and is absolutely prevented from falling over prematurely by the fact that the finger overlaps the plate to a considerable depth. This depth may be almost equal to the distance

between two immediately adjacent pivots a^1 , or b^1 , or c^1 , as the case may be, because the number-plate a , or b , or c , which is arranged to fall over, is lowered to an extent equal to that distance. Consequently the greatest 70 jolting of the vehicle on which the fare indicator is mounted, will not be able to cause the number-plate to fall over prematurely.

The extensions r , besides making substantially a continuous plate out of two adjacent 75 plates when in indicating position, also serve another very important purpose, to wit: They make of each plate a lever of the first order, that is with the fulcrum between the power and the weight, the pivot a^1 being the 80 fulcrum, the weight of the main body of the plate the power, and the preceding plate the weight. In advancing, the extension of each plate bears against the preceding plate and when the latter is in indicating position, 85 against the stop or finger a^3 , it is held there by the weight and leverage of the succeeding plate.

The three counters are operated from a common shaft w , by means of a cam-toothed 90 wheel d which is driven at a greater or less speed (according to the tariff for which the apparatus is set by the driver), from a wheel of the vehicle, or by the clockwork, in the usual way. This wheel d lifts slowly a lever 95 e fixed on the shaft w , and when this lever has passed over the highest point of each cam-tooth of the wheel it allows it to drop suddenly under the action of a spring f . On the same shaft w are fixed levers a^4, b^4, c^4 , 100 which serve to advance the three counters by means of the pawls a^5, b^5, c^5 .

A ratchet wheel b^6 with which the pawl a^5 engages is fixed to the roller a^2 . At each drop of the lever e the counter is advanced 105 one division, whereby the next following number is displayed.

The pawl b^5 which is connected to the lever b^4 is normally prevented from engaging with the ratchet wheel b^6 , by the following means:— 110 The left flange of the roller a^2 has a somewhat larger diameter than the adjacent ratchet wheel b^6 . The forward edge of the pawl b^5 is made of such a width that it will lie on the flange of the roller a^2 , and therefore will not 115 engage with the ratchet wheel b^6 during the quick advance of the lever b^4 , but will slip idly over the flange of the roller a^2 . But before the first counter moves from 90 to 0, the pawl b^5 falls into a gap a^7 (Fig. 2) and thus 120 engages with the ratchet wheel b^6 , so that on the next following drop of the lever, the second counter also will be advanced. At the next following drop of the lever e , the pawl b^5 has already moved out of engagement 125 again with the ratchet wheel b^6 . Similarly the pawl c^5 is normally prevented from engaging with the ratchet wheel c^6 of the third counter by the fact that the pawl c^5 rests on the left flange of the roller b^2 adjacent to the 130

ratchet wheel c^6 . It is only when the second counter is advanced from 9 to 0, that the pawl c^5 comes into engagement with the ratchet wheel c^6 and thus advances the third counter.

5 When the fare-indicator is brought out of operation each of the three counters must be reset automatically and simultaneously into its zero position, or into its initial position. For this purpose, the three rollers a^2 , b^2 , c^2 , of 10 the three counters are mounted side by side on a shaft g (Fig. 4) which is capable of axial but not of rotary motion, where as the rollers themselves can rotate, but cannot move axially. To each roller there is connected a 15 complete thread of a quick-pitched screw a^8 , b^8 , c^8 , respectively. During the operative position of the apparatus, studs a^9 , b^9 , c^9 , fixed on the slideable but not rotatable shaft g , are shifted so far to the left as to keep them 20 out of engagement with the screw threads.

In bringing the apparatus out of operation, the shaft g is shifted to the right so as to bring the studs a^9 , b^9 , c^9 , into engagement with the screw-threads a^8 , b^8 , c^8 , respectively, 25 whereupon the latter are rotated, together with their rollers a^2 , b^2 , c^2 , until each stud has reached the lowest point of its corresponding screw-thread. The rotary motion has the same direction as that of the advance of the 30 several counters. Therefore by shifting the shaft g into its extreme right hand position, each of the rollers a^2 , b^2 , c^2 will be pushed forward into a determined position. This determined position of each roller produces a 35 determined indication of the respective counter, namely, the zero or initial position.

Spiral surfaces may be used instead of the screw-threads above referred to, but in that case, the studs a^9 , b^9 , c^9 must be moved at 40 right-angles to the axis of the shaft g , instead of the axial direction thereof as above described.

In the example shown, the shaft g is prevented from rotating by means of a bar h 45 (Fig. 3) which is fixed thereto, and is guided in the frame i of the counter by means of a rod k fixed to the bar h . A spring g^1 imparts to the shaft g a constant tendency to return into its extreme left position, which corresponds with the operative position of the 50 fare-indicator. To bring the fare-indicator into its inoperative position, a shaft m^1 is rocked so as to press the pin m of its crank m^2 , against the bar h , whereby the shaft g is 55 moved into its extreme right hand position. By this movement all three counters are advanced into the zero or initial position. Since this setting to zero takes place in the 60 same direction of rotation as that in which the ratchet wheel a^6 , b^6 , c^6 are advanced by the driving pawls a^5 , b^5 , c^5 it is not necessary to place these pawls out of engagement with their ratchet wheels as is the case each time in the devices for setting the counters employed hitherto back to zero. Nor is it neces-

sary to place the retaining-catches, or in their stead the springs a^{10} , b^{10} , c^{10} employed in the example shown to engage with the ratchet wheels a^6 , b^6 , c^6 , out of engagement with said ratchet wheels, so that this feature 70 constitutes a further simplification in the construction and operation of fare-indicators. On the other hand the herein-described setting to zero renders it necessary that immediately successive positions of the rollers 75 which carry the number plates, shall be at a considerable angular distance apart (36 degrees in the example shown). This insures that the studs a^9 , b^9 , c^9 shall have a secure engagement with the respective screw-threads 80 a^8 , b^8 , c^8 in the position which follows immediately on the zero position.

The rollers carrying the number-plates must be advanced intermittently and not continuously, because in the latter case, the 85 screw threads a^8 , b^8 , c^8 (or the equivalent spirals) might possibly take up such positions relatively to their corresponding studs a^9 , b^9 , c^9 that a stud in advancing, might come against the highest point of its corresponding 90 screw thread or spiral, without being able to produce the zero position.

A further reason for moving the counters intermittently for the purpose in view, is that if the first roller a^2 were moved continuously, 95 then, although it would produce a sudden change in the visible number at the moment that the upper edge of the foremost upper number-plate was passing under the lower edge of the finger a^3 , yet the hereinbefore 100 specified security against a premature falling over of the upper plate would be absent, and further, it would be impossible to obtain by means of an adding mechanism the total sum of the indications, and to provide a guarantee 105 that at the same instant the amount indicated by the indicator increases by a unit, the total sum indicated by the adding mechanism shall also be increased by a unit. The reason for this difficulty is that in such an arrangement the advance of the adding mechanism would have to be produced by means of a special eccentric or the like connected to the roller a^2 , and then, even with the most accurate adjustment, it would be 110 almost impossible to insure that the adding-mechanism shall be advanced always at the exact instant of the falling over of the corresponding number-plate.

In the example shown, the advance of the 120 adding-mechanism is produced as follows:— The lever e which is actuated by the cam wheel d , has connected to it a pawl n which operates in the usual manner a counter o whose indications are visible through an 125 aperture o^1 . This check-counter adds and records the total forward movements of the counters of the indicator and thus records the total receipts.

The apparatus according to this invention 130

can be readily put together, and each counter can be adjusted separately.

The quick-pitched screw threads a^8 , b^8 , c^8 (Fig. 4) are constructed as sleeves which are capable of rotation on the shaft g , and themselves serve as hubs for the rollers a^2 , b^2 , c^2 . The ratchet wheels a^6 , b^6 , c^6 are fixed directly on these sleeves. The cylindrical shoulder b^{11} of the sleeve b^8 serves as a bearing for the roller a^2 , and the cylindrical shoulder c^{11} of the sleeve c^8 serves as a bearing for the roller b^2 . The cylindrical shoulder p^1 of a liner p serves as a bearing for the roller c^2 . As shown in Fig. 4, the internal width of the frame i is completely filled up by the liner p of the roller c^2 , sleeve c^8 , roller b^2 , sleeve b^8 , roller a^2 and sleeve a^8 so that the rollers cannot shift laterally once the counters have been put together. On the other hand, the several counters may be adjusted in succession with reference to their respective zero positions, by mounting the sleeve a^8 on the shaft g and adjusting its zero position, and then mounting the roller a^2 and the sleeve b^8 and adjusting the zero position of the latter and finally mounting the roller b^2 and sleeve c^8 and adjusting the zero position of last counter.

The improved apparatus may also be employed for indicating and recording extra charges made by the driver for luggage, empty return-journeys, &c. In such case, instead of operating the lever e by the cam-wheel d (whose motion depends on the length or duration of the journey, or on both together) the requisite motion must then be imparted to the lever e by means of an eccentric operated by the driver.

I shall not make any claim herein to the zero resetting means, the same forming the subject matter of a separate application for Patent 2,429,334 filed April 27 1908.

Having thus described my invention, what I claim as new and desire to secure by Letters Patent is:—

1. The combination, in a fare indicator, of a roller, a series of plates pivotally mounted thereon near the periphery thereof, one of said plates being retained stationary in indicating position while the roller is at rest, a continuously rotatable element, and connections between said element and the roller for rotating the roller one step and moving the plate from the indicating position, at a predetermined point in the rotation of the continuously rotatable element.

2. The combination, in a fare indicator, of a roller, a series of plates pivotally mounted thereon near the periphery thereof, a stop in the path of movement of the plates when the roller is rotated, one of the plates being held stationary against the stop in indicating position while the roller is at rest, a continuously rotatable element, and connections between

said element and the roller for rotating the roller one step and moving the plate from the indicating position, at a predetermined point in the rotation of the continuously rotatable element.

3. The combination, in a fare indicator, of a roller, a series of plates pivotally mounted thereon near the periphery thereof, a stop in the path of movement of the plates when the roller is rotated, one of the plates being held stationary against the stop, in indicating position, while the roller is at rest, by a trans-pivotal extension on the next succeeding plate, a continuously rotatable element, and connections between said element and the roller for rotating the roller one step and moving the plate from the indicating position at a predetermined point in the rotation of the continuously rotatable element.

4. The combination, in a fare indicator, of a roller, a series of plates pivotally mounted thereon near the periphery thereof, a stop in the path of movement of the plates when the roller is rotated, one of said plates being held stationary in indicating position while the roller is at rest, a continuously rotatable element, a registering mechanism, and connections from the continuously rotatable element to the roller and the registering mechanism for simultaneously rotating the roller one step, moving the plate from the indicating position, and actuating the registering mechanism one step forward at a predetermined point in the rotation of the continuously rotatable element.

5. The combination, in a fare indicator, of a roller a series of plates pivotally mounted thereon near the periphery thereof, a stop for holding one of said plates in indicating position when the roller is at rest, the plate being held stationary against the stop, a continuously rotatable element, a spring pressed pawl adapted to engage the roller and actuate it one step at a time in a forward direction and to free the indicating plate from the stop, and means actuated by the rotative element for holding said pawl inactive during predetermined portions of the rotation of said element and releasing it for action at the end of each of said periods.

6. The combination, in a fare indicator, of a roller, a series of plates pivotally mounted thereon near the periphery thereof, a stop in the path of movement of the plates when the roller is rotated, one of said plates being held stationary against the stop in indicating position while the roller is at rest, a continuously rotatable element, a spring pressed pawl adapted to engage the roller and actuate it one step at a time in a forward direction and to free the indicating plate from the stop, and a cam wheel carried by said continuously rotatable element for holding said pawl inactive during predetermined portions

of the rotation of said element and releasing it at the end of each of said periods.

7. The combination, in a fare indicator, of a roller, a series of plates pivotally mounted thereon near the periphery thereof, a stop in the path of movement of the plates when the roller is rotated, one of said plates being held stationary against the stop in indicating position while the roller is at rest, a continuously rotatable element, a registering mechanism, a ratchet wheel on the roller, a ratchet wheel on the registering mechanism, a spring pressed pawl engaging these ratchet wheels adapted to simultaneously actuate them one step at a time in a forward direction, and means actuated by the continuously rotatable element for holding both pawls inactive during predetermined portions of the rotation of said element and simultaneously releasing them for action at the end of each of said periods.

8. The combination, in a fare indicator, of a roller, a series of plates pivotally mounted thereon near the periphery thereof, a stop against which one of said plates rests stationary when in indicating position, of an extension on each plate beyond its pivot adapted

to bear against the preceding plate and hold it against said stop in indicating position.

9. The combination, in a fare indicator, of a roller, plates pivoted thereon near its periphery, a stop in the path of movement of the plates when the roller is rotated said plates being held stationary, as the roller is rotated, against said stop in indicating position, a shaft parallel with the roller, a continuously rotating element, an arm on the shaft, a pawl on said arm engaging the roller, a second arm on said shaft, a cam wheel on the continuously rotating element for periodically actuating the second arm and with it the shaft, the first arm and the pawl, and a spring acting on one of the arms with a tendency to move the roller forward when the pawl is periodically released by the cam wheel.

In testimony whereof I have signed my name to this specification in the presence of two subscribing witnesses.

PAUL RICHERT.
